METHOD AND MEANS FOR CONTROLLING
DEEP WELL GUNFIRE FOR PERFORATING
CASINGSWilfred G. Lane, Los Angeles, Calif., assignor to
The Technicraft Engineering Corporation, Los
Angeles, Calif., a corporation of California

Application December 20, 1932, Serial No. 648,049

25 Claims. (Cl. 81—188)

The present invention is a method and means for controlling deep well gun-fire for perforating casing, and relates to a type of perforating gun disclosed in a co-pending application for patent filed by me on November 12, 1932, Serial Number 642,410.

The primary object of the invention is to provide means, controlled from the mouth of the well, for setting off, electrically, a series of explosive charges distributed thruout the length of a gun-body for the purpose of perforating a well casing into which said gun-body has been lowered.

In the application above mentioned a cable is shown which transmits the energy required to energize thermal elements for firing charges behind projectiles.

In the present disclosure the cable is not used. A battery is lowered with the gun on a dry tubing string and the electrical contact connections, necessary to operate the gun, are made and broken in response to accumulation and release of fluid pressure within the tubing string.

In the accompanying drawing, Figure 1 is a vertical central cross section of a well bore, cased and cemented, within which is shown, partly in section and partly in elevation, by control unit, perforating gun and means for anchoring same to the well casing.

Figure 2 is a section of Figure 1, taken on the line II—II.

Figure 3 is a section of Figure 1, taken on the line III—III.

Figure 4 is a detail view showing a float tank for operating a valve.

Figure 5 is a view of the parts shown in Figure 4, showing the tank raised by liquid to actuate the valve.

Figures 6 and 7 are, respectively, collapsed and distended views of a sylphon or bellows, and illustrate the relative positions of elements actuated thereby.

Figure 8 is a section of Figure 6 taken on the line VIII—VIII.

Figure 9 is a view similar to Figure 8, illustrating the step-by-step advance of a contact arm by reciprocation of the sylphon, and

Figure 10 is a detail view of a pawl.

Referring to the drawing, Figure 1, the numeral 1 indicates a casing surrounded by cement 2 fitting a well bore extending through formation 3.

A dry tubing string 4 is threaded at its lower end with a head member 6 into which is also threaded the upper end of a mandrel 7, the lower end of which is threaded at 8 into the head member 9 of a gun-body.

Slidable on a mandrel 7 is a cage consisting of collars 11 joined by bow springs 12 which bear frictionally against the wall of casing 1.

The upper of collars 11 carries a hook 13 which engages a stud 14 extending outwardly from mandrel 7.

Slips 16, secured at one end to upper collar 11 are provided with serrated outer surfaces 17 for engaging the casing wall.

When the device is run in the hook 13 engages stud 14 and slips 16 are out of engagement with the casing wall. When the device is to be anchored, however, tubing string 4 is rotated to the left, thereby disengaging hook 13 and the tubing string lowered through the spring cage, which 15 is held stationary by the contact of springs 12 with the casing wall.

Slidable on mandrel 7 is a cone member 18. Interposed between said cone and head member 6 is a plurality of packing rings 19 and spacing rings 20 21.

Downward movement of tubing string 4 depresses head 6 until it encounters the uppermost of spacing rings 21, and the ring assembly is moved downwardly, causing the core 18 to spread 25 slips 16, the wedge action causing the serrations 17 to engage the wall of casing 1. The weight of the tubing string 4 compresses the packing rings which are deformed laterally dividing the casing into upper and lower zones.

The device so far described is a hook wall packer shown and claimed in a co-pending application for patent filed June 1, 1932, Serial No. 614,731.

It is here employed as an anchoring means for structure hereinafter described.

The gun body here shown is similar to that disclosed in my co-pending application Serial Number 642,410 filed November 12, 1932.

Said body is composed of a number of screw 40 threaded cylindrical sections 22, provided with axial bores 23 registering one with another to provide a conduit for wires 24.

Intercepting said bores 23 are transverse bores into which are threaded at 26 removable breech 45 blocks 27, concentrically bored to receive removable barrels 28, threaded thereinto at 29.

In the bore 31 of each barrel 28 is a projectile 32 to which is spot welded a disc 33 which serves dual purposes. It forms a means of retarding 50 projectile 32 and constitutes a seal against hydrostatic pressure when compressed between the bottom of the bore in breech-block 27 and the inner end of barrel 28.

A combustion chamber 34 contains a thermal 55

element 36 for igniting an explosive charge to shear disc 33 and expel projectile 32.

Electrical energy is carried to the thermal element 36 by the wires 24 each of which is connected at one end to a contact finger 37 contacting one end of thermal element 36, which is grounded at the other end through disc 33 to the gun body.

The upper most section 22 of the sectional gun body is thread-connected at 38 to a length of tubing 39, which houses storage battery cells indicated at 41.

Tubing section 39 is thread connected at 42 to a similar section 43 similarly threaded at 44 15 to another section 46, which, in turn, is threaded at 47 to the head member 9 of the gun body.

Supported in the space between the adjacent ends of tubing sections 39 and 43 is a circular disc 48, Figures 1 and 3, of insulative material 20 through which extend a series of contact members 49 disposed in circular relation to be successively contacted by a contact arm 51.

Each of wires 24 is connected, at one end, to a contact 49 and, at the opposite end, to a spring 25 contact finger 37. The terminals A—B of battery 41 are connected, A to ground on the body, as at 52, and B to the contact arm 51, so that if said arm be rotated to successively wipe contacts 49, the thermal elements 36 will be energized, one by 30 one, and projectiles 32 be expelled to perforate casing 1 and cement 2.

I will now describe means for imparting intermittent, step-by-step rotary movement to contact arm 51 in response to fluid pressure transmitted through the dry tubing string 4 to perforate casing 1; means for entrapping a sample of fluid, admitted through perforations, within the tubing string; and means for preventing premature fire.

40 In Figures 1, 6, and 7, I show a cup member 53 to the bottom of which is secured the contact arm 51 the parts being insulated, one from the other, by a disc 54. A stud 55 on contact arm 51 extends into a bore through platform 48 pivoting said arm and forming a connection for battery wire B.

45 The vertical annular wall of cup 53 is serrated to form ratchet teeth 56 having vertical and oblique edges. Extending into cup 53, in slidable relation, is a tubular closed end 57 of a sylphon 50 or bellows 58, the integral flanged base 59 of which is secured between the adjacent ends of tubing sections 43 and 46, Fig. 1.

When air, under pressure, from tubing string 4 enters sylphon 58 thru an inlet passage 61, Fig. 55 1, said sylphon is distended from the position shown in Fig. 6 to that shown in Fig. 7 and the reciprocative movement of said sylphon is made to impart step-by-step rotative movement to cup 53 (and contact arm 51 secured thereto) by a pawl 62 pivoted on a stud 63 extending from member 57 of the sylphon.

60 Said pawl is normally held in the full line position shown in Figures 6 and 10 by a coiled tension spring 64, one end of which is secured to said pawl at 66 and the other end of which is anchored to member 57 at 67.

65 Pawl 62 has an arcuate notch 68, formed on a circle struck with the pivot pin 63 as a center, for engaging a stud 69 extending outwardly from member 51.

70 When sylphon 58 is distended the descending pawl 62 encounters an oblique edge of one of the ratchet teeth 56, causing the cup 53 to rotate to the position shown in Figure 7, the vertical edge

of said ratchet tooth moving pawl 62 to its dotted line position Figures 6 and 10.

Cup 53 is provided with ratchet teeth 71, which are engaged by a detent 72 secured to the wall of tubing section 43.

5 The cup is thus prevented from reverse movement and, when pressure in tubing string 4 is relieved, sylphon 58 collapses until the pawl 62 clears the ratchet teeth 56, at which time spring 64 restores said pawl to its initial position, clearing the point of the ratchet tooth, for engagement with its oblique surface for repeated operation.

In Figures 1, 4, and 5, I show a means for preventing premature or accidental firing of the gun from hydraulic pressure, in case the tubing string 4 leaks, it being understood that the packer and gun are lowered through a column of heavy fluid such as rotary mud or water which fluid serves to balance the pressure of the forma- 20

tion. At 73 I show studs integral with, or secured to, the member 59 of the sylphon. Said studs carry pintles 74 on which are pivoted levers 76, the inner ends of which extend into an annular groove 77 in the stem of a conically pointed valve 78 adapted to seat within and close the inlet 61 of sylphon 58.

Levers 76 are so weighted or balanced on their pivots as to normally support valve 78 in its in- 30 operative position (Figure 4). The ends of said levers, remote from said valve, are secured by chains 79, to legs 81 on an air tight container 82.

Container 82 is of relatively light material, is fluted on its periphery, as indicated at 83, to by- 35 pass air from tubing string 4 to inlet 61 of sylphon 58, and is adapted, by its buoyancy, to lift, when liquid 84 enters tubing section 46, and thereby depress valve 78 closing inlet 61 before sufficient hydrostatic head can accumulate to 40 operate sylphon 58.

In order to withdraw and entrap a sample of fluid admitted to casing 1 through perforations made by gun-fire, I provide the following means:—A section of tubing 86 is connected at 45 one end to head member 9 and at the other to the uppermost of the gun-body sections 22, by threads, by welding, or in any suitable manner providing an annular, air tight chamber 87, enclosing the uppermost of gun barrels 28, as shown 50 in Figure 1. By pre-arrangement the wires 24 are so connected to contact disc 48 that the projectile 32 in that barrel 28 (which is enclosed by the tubing section 86) is the last to be discharged.

When the last shot has been fired, the projectile 32 pierces the wall of tubing 86, allowing the surrounding liquid, which has been released from formation through perforations made by gun-fire, to enter chamber 87, whence it passes thru ports 88 in tubing sections 46, and through 60 a passage 89 in head 9, to the dry tubing string 4.

Being thus released to atmosphere, said liquid builds up a head within the tubing string to a level determined by formation pressure.

A ball, indicated in dotted lines at 91, is dropped 65 thru the tubing string from the mouth of the well to close passage 89 and entrap the fluid accumulated in the string.

Operation

70 The method of operation of my invention is as follows:—The parts, assembled as shown in Figure 1, are lowered in casing 1 to a point of depth at which the casing is to be perforated, on a dry tubing string 4.

The said string is rotated to set the anchoring means, holding the gun body suspended within the casing 1.

The upper open end of tubing string 4 is connected to a source of air or gas, under pressure, and sufficient pressure admitted through the tubing string to distend sylphon 58, causing contact arm 51 to close the electrical circuit firing a projectile 32.

10 Pressure in tubing string is then relieved, whereupon sylphon 58 contracts due to inherent resiliency, and the mechanism is restored to initial position for repeated operation until the last shot is fired, which opens the tubing string to admission of fluid from the newly-perforated formation.

15 Ball 91 is dropped to entrap the sample and the entire device is withdrawn from casing 1 by lifting the tubing string and rotating it to re-20 engage hook 13 and stud 14.

I claim:—

1. Apparatus for perforating well casing or the like comprising a tubing string, a gun body, connected to said tubing string, provided with a plurality of gun units each adapted, when discharged, to drive projectiles through a surrounding casing, and coactive means carried by said tubing string and said gun body, responsive to successive accumulations and releases of pressure within 30 said tubing string for successively discharging projectiles from the several gun units.

2. Apparatus for perforating well casing and the like comprising in combination, a dry tubing string, a gun body, supported by said tubing string, provided with explosive means adapted, when discharged to drive projectiles through a surrounding casing, control means, including an electrical circuit for discharging said explosive, and pneumatic means operable through said tubing string for actuating said control means.

3. A well tool adapted to be lowered in a well casing and comprising in unitary relation an explosive actuated means; electrical operating mechanism therefor; and a fluid responsive device for controlling said mechanism.

4. A well tool adapted to be lowered in a well casing and comprising a body structure, explosive actuated means carried thereby; an electrical operating mechanism including conductors 50 communicating with said means; and a fluid responsive device for controlling said mechanism.

5. A well casing perforator comprising a body structure; a gun unit carried thereby arranged to fire a projectile laterally through a surrounding well casing; an electrical operating mechanism including a conductor communicating with said gun unit, and a fluid responsive device for controlling said mechanism.

6. In a well tool; a tubing string; a body structure suspended therefrom; an explosive actuated means carried by the body structure, an electrical operating mechanism for said means; and a fluid pressure actuated device for controlling said mechanism, said device positioned in responsive relation with fluid contained in said tubing string.

7. A well casing perforator comprising a tubing string; a body structure suspended therefrom; and a gun unit carried by said body structure arranged to fire a projectile laterally through a surrounding well casing; an electrical operating mechanism including a conductor communicating with said gun unit; and a fluid pressure actuated device for controlling said mechanism, said device positioned in responsive relation with fluid 75 contained in said tubing string.

8. In a well tool; a tubing string; a body structure suspended therefrom; an explosive actuated means; an electrical operating mechanism for said means; a pneumatic control device for said mechanism positioned in responsive relation to 5 the interior of said tubing string whereby variation in pressure in said tubing string actuates said device; and means for isolating said control device from the tubing string upon entrance of liquid.

9. A well casing perforator comprising a tubing string; a body structure suspended therefrom; a gun unit carried by said body structure arranged to fire a projectile laterally through a surrounding well casing; an electrical operating mechanism including a conductor communicating with said gun unit; a pneumatic control device for said mechanism positioned in responsive relation to the interior of said tubing string whereby variation in pressure in said tubing string actuates 20 said device; and means for isolating said control device from the tubing string upon entrance of liquid.

10. The combination with a gun type perforator for well casings; said perforator having a 25 plurality of guns; of an electrical firing mechanism mounted within said perforator and arranged to discharge the guns thereof; and fluid responsive means for controlling said firing mechanism.

11. The combination with a gun type perforator for well casings; said perforator having a plurality of guns; of a tubing string supporting the perforator; of an electrical firing mechanism mounted within said perforator and arranged to 35 discharge the guns thereof; and a fluid responsive means for controlling said firing mechanism, said means positioned in responsive relation to pressure within the tubing string.

12. The combination with a gun type perforator for well casings; said perforator having a plurality of guns; of a tubing string supporting the perforator; and an electrical firing mechanism mounted within said perforator and arranged to discharge the guns thereof; a pneumatic control device for controlling said firing mechanism, said device positioned in responsive relation to the interior of the tubing string whereby by variation in pressure therein actuates said device; and means for isolating said control device 50 from the tubing string upon entrance of liquid.

13. A well tool adapted to be lowered in a well casing and comprising in unitary relation a plurality of explosive actuated means; a fluid responsive device; ratchet means engageable thereby to advance upon successive operations of said device; and an electric circuit including contacts engageable in successive order by said ratchet means and conductors leading therefrom to said explosive actuated means to connect the same 60 sequentially in said electric circuit.

14. In a well tool; a tubing string; a body structure suspended therefrom; a plurality of explosive actuated means carried by the body structure; a fluid responsive device; ratchet means engageable thereby to advance upon successive operations of said device; and an electric circuit including contacts engageable in successive order by said ratchet means and conductors leading therefrom to said explosive actuated means to 70 connect the same sequentially in said electric circuit; said fluid responsive device positioned in responsive relation to fluid contained in said tubing string.

15. In a well tool; a tubing string; a body struc- 75

ture suspended therefrom; a plurality of explosive actuated means carried by the body structure; a fluid responsive device; ratchet means engageable thereby to advance upon successive operations of said device; an electric circuit including contacts engageable in successive order by said ratchet means and conductors leading therefrom to said explosive actuated means to connect the same sequentially in said electric circuit; and buoyant means for isolating said fluid responsive device from the tubing string upon the entrance of a liquid therein.

16. The combination with a gun type perforator for well casings said perforator having a plurality of guns; of a fluid responsive device; ratchet means engageable thereby to advance upon successive operations of said device; and an electric circuit including contacts engageable in successive order by said ratchet means and conductors leading therefrom to the guns of said perforator to connect the same sequentially in said electric circuit.

17. The combination with a gun type perforator for well casings, said perforator having a plurality of guns; and a tubing string supporting the perforator; of a fluid responsive device; ratchet means engageable thereby to advance upon successive operations of said device; an electric circuit including contacts engageable in successive order by said ratchet means and conductors leading therefrom to the guns of said perforator to connect the same sequentially in said electric circuit; and buoyant means for isolating said fluid responsive device from the tubing string upon the entrance of a liquid therein.

18. In a well tool; a body structure; a plurality of explosive actuated means; and an operating means therefor comprising an electrical operating mechanism connectible with the several explosive actuated means in a predetermined order; and a fluid responsive device actuated by successive accumulations and releases of fluid pressure and engageable with said mechanism to connect the same in said predetermined order with the several explosive actuated means to fire the same.

19. A well casing perforator comprising a body structure, a plurality of gun units carried thereby arranged to fire projectiles laterally through a surrounding well casing; and an operating means therefor comprising an electrical operating mechanism connectible with the several gun units in a predetermined order; and a fluid responsive device actuated by successive accumulations and releases of fluid pressure and engageable with said mechanism to connect the same in said predetermined order with the several gun units to fire the same.

20. In a well tool; a body structure; a plurality of explosive actuated means; and an operating means therefor comprising, an electrical operating mechanism connectible with the several explosive actuated means in a predetermined order; and a fluid responsive device actuated by successive accumulations and releases of fluid pressure

and engageable with said mechanism to connect the same in said predetermined order with the several explosive actuated means to fire the same; and a tubing string for supporting the body structure; said fluid responsive device positioned in responsive relation to fluid within said tubing string.

21. A well casing perforator comprising a body structure; a plurality of gun units carried thereby arranged to fire projectiles laterally through a surrounding well casing; and an operating means therefor comprising an electrical operating mechanism connectible with the several gun units in a predetermined order and a fluid responsive device actuated by successive accumulations and releases of fluid pressure and engageable with said mechanism to connect the same in said predetermined order with the several gun units to fire the same; and a tubing string for supporting the body structure; said fluid responsive device positioned in responsive relation to fluid within said tubing string.

22. The combination with a gun type well casing perforator carrying a plurality of electrically operable gun units; of an electrical firing mechanism mounted within said perforator and arranged to discharge the gun units thereof; switch means interposed between the firing mechanism and gun units; and a fluid responsive device co-actively associated with said switch means and actuated by successive accumulations and releases of pressure to connect said firing mechanism through said switch means with the several gun units successively.

23. The combination with a gun type well casing perforator carrying a plurality of electrically operable gun units and adapted to be lowered in a well casing by a tubing string; of an electrical firing mechanism mounted within said perforator and arranged to discharge the gun units thereof; switch means interposed between the firing mechanism and the gun units; and a pneumatic device positioned in responsive relation to pressure within the tubing string and coactively associated with said switch means to actuate the same in response to successive accumulations and releases of pressure within the tubing string and cause the gun units to discharge successively.

24. A method of perforating well casing in situ characterized by lowering on a tubing string a plurality of gun units into said casing while maintaining a pneumatic communication with the tubing string, then discharging said gun units successively by successive pneumatic impulses.

25. A method of perforating well casing in situ characterized by maintaining a pressure balancing liquid within said casing; lowering by a tubing string a plurality of gun units into said casing while maintaining pneumatic communication with the tubing string, but insulated from said pressure balancing liquid; then discharging said guns successively by successive pneumatic impulses.

WILFRED G. LANE.
